CLAIM

The ornamental design for a wall mount, as shown and described.

DESCRIPTION

FIG. 1 is a front perspective view of a wall mount showing our new design;

FIG. 2 is another front perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines depicting the remainder of the wall mount in FIGS. 1-4 show features that form no part of the claimed design.

1 Claim, 6 Drawing Sheets
